(57) **CLAIM**

The ornamental design for a necklace, as shown and described.

DESCRIPTION

FIG. 1 is a front, right-side, top perspective view of the necklace;

FIG. 2 is a front elevational view thereof;

FIG. 3 is a rear portion of a top plan view thereof, with the dot-dash chain line bisecting between the rear portion of a top plan view (FIG. 3) and the front portion of the top plan view (FIG. 4);

FIG. 4 is a front portion of a top plan view thereof, with the dot-dash chain line being bisecting between the rear portion of a top plan view (FIG. 3) and the front portion of the top plan view (FIG. 4);

FIG. 5 is a right-side elevational view thereof;

FIG. 6 is a rear elevational view thereof;

FIG. 7 is a bottom plan view thereof; and,

FIG. 8 is a rear, right-side, bottom perspective view thereof.
